[57] CLAIM

The ornamental design for a toy razor, as shown and described.

DESCRIPTION

FIG. 1 is a perspective view of a toy razor showing my new design, the texture of small circles simulating openings being an overall pattern through the areas in which the texture is partially shown in FIGS. 1, 2, and 5; FIG. 2 is a top plan view thereof; FIG. 3 is a front elevational view thereof; FIG. 4 is a bottom plan view thereof; FIG. 5 is a rear elevational view thereof; FIG. 6 is a right side elevational view thereof; and, FIG. 7 is a left side elevational view thereof.

FIG.1.
